UNITED STATES PATENT OFFICE.

PHILIP VON ZEIPEL, OF DUQUESNE, PENNSYLVANIA.

GRATE FOR FURNACES.

1,105,054.

Specification of Letters Patent. Patented July 28, 1914.

Application filed July 2, 1910. Serial No. 570,103.

To all whom it may concern:

Be it known that I, PHILIP VON ZEIPEL, a resident of Duquesne, in the county of Allegheny and State of Pennsylvania, have invented a new and useful Improvement in Grates for Furnaces; and I do hereby declare the following to be a full, clear, and exact description thereof.

My invention relates to grates for furnaces, and particularly to grates for use with gas producers. Its object is to provide a grate construction which will completely and continuously eliminate the accumulated ash and clinker and at the same time prevent the injurious intake of air except through the regular means for introducing the air.

To these ends my invention consists, generally stated, in a furnace having a rotary fuel supporting portion or grate proper beneath the fuel or fire bed, and a surrounding clinker platform, a side discharge therefrom, and means for scraping the clinker from the clinker platform comprising a removable scraper or plate extending to the grate portion proper and preferably inserted through a guideway. It also consists in other features of construction as more particularly described hereinafter.

In the drawings, Figure 1 is a vertical section illustrating my invention as applied to a gas producer; and Fig. 2 is a horizontal section on the line 2—2 Fig. 1.

While I have illustrated my invention as applied to a gas producer, for which it is primarily designed, it will be understood that it is not limited thereto, but includes all uses to which it may be put within the scope of the claims. The gas producer 1 has the cylindrical shell 2 resting on the bed plate 13 and carrying the refractory lining 3 which rests at its base on the ring plate 4 secured to the metallic shell. Mounted in the lower part of the producer 45 is the grate or fuel support 6, which may be of any desired construction, being illustrated as of pyramidal shape extending up into the fire chamber 7, the apex of the pyramid eccentrically located to the movement of the grate and acting to agitate the fuel in the fire chamber. The grate is supported on the annular wall 8, which in turn rests upon the platform 9, said platform 50 resting upon the annular bearing 10, rotatably mounted on the rollers 11 secured in the brackets 12 on the bed plate 13. The plat-

form 9 extends outwardly close to the shell 2 and under the plate 4 supporting the refractory lining thus forming a clinker chamber 14 extending from the grate outwardly to the inclosing shell below the lining 3, and into which the ash and clinker will pass from the grate 6. The grate with its clinker platform is rotated by any suitable means such as by the pinion 15 engaging with the 60 rack face 16 on the lower face of the platform 9, said pinion being carried on the shaft 17 extending through the shell 2 and driven by any suitable power. On the same level with the clinker receptacle 14 is a side 65 opening 18 leading into a chute 19, said discharge opening being normally closed by a door 20. The chute 19 discharges into any suitable ash cart 21 by which the ash and clinker can be carried away. To remove 70 the clinker and ash from the grate, I provide at one side of the opening 18 a suitable guideway 23 in line with the horizontal clinker platform 9 and extending up to the plate 4 supporting the refractory lining and 75 adapted to receive a suitable scraper 24 which extends through such guideway over the platform 9 and when fully inserted to the grate supporting wall 8 so that upon the rotation of the grate the scraper deflects the clinker and ash outwardly through the chute 19 and into the ash cart 21, scraping over the entire platform and completely 80 cleaning the same. The scraper 24 may be, if desired, removed in case the clinker has 85 become jammed in any manner or it is not desired to rotate the grate or not necessary to use the scraper.

The grate is preferably operated by air blast entering through the air pipe 26, and 90 for that reason the fuel support 6 is preferably made in some grate or open-work form so that a small portion of ash may pass through the same into the central air chamber 27 under the fuel support 6. The 95 chamber 27 terminates in the ash receptacle 28, the same being provided with a side outlet 29 closed by a suitable door 30. Any such ash dropping through the grate is directed down into the ash receptacle 28 and 100 past the rollers supporting the grate by the inwardly inclined chute 31 carried by and rotating with the grate.

When the grate is in use the furnace or producer is employed in the usual way with 110 either a natural draft or an induced draft, such as through the air-pipe 26, and as the

fuel is ignited, it naturally arches over within the fire chamber and gradually descends as combustion proceeds. The clinker and a portion of the ash work downwardly over 5 the grate surface and into the clinker receptacle 14. The grate may remain stationary or be rotated as found desirable, and in the latter operation the eccentrically pyramidal grate will act to agitate the fuel 10 so that the clinker and ash will gather within the clinker receptacle which by extending under the refractory lining of the furnace provides for the collection of a large amount 15 of clinker. To remove this clinker and ash it is only necessary to open the door 20 and insert the scraper 24 within the guideway 23 on the same level as the clinker chamber and by the rotation of the grate, the clinker gathered within the clinker chamber is 20 deflected and ejected through the chute 19 into the ash cart, the chamber being completely cleaned in this way, and after which the scraper is withdrawn and the door closed and the furnace continues to operate 25 as before.

But little ash will gather in the ash receptacle 28 under the central fuel support or grate and the same can be removed when necessary by an ordinary scraper through 30 the door 30. The grate occupies relatively little space and provides for the side discharge of the clinker by a simple operation, while by operating with the pyramidal grate it collects the mass of the clinker and 35 provides for its easy discharge without interfering with the regular operation of the furnace.

What I claim is:

1. A gas producer having in combination 40 a rotatable grate comprising a centrally located grate portion proper provided with openings adapted to admit the air or steam blast, an annular wall carrying said grate portion, an annular horizontal clinker platform around said wall and at a lower level than said grate portion, an outer shell or 45 wall and a refractory lining carried thereby and terminating above said clinker platform

to thereby provide a clinker receptacle thereon, said shell having an outlet from said receptacle, and a scraper at said outlet and extending completely across said clinker receptacle flush with said refractory lining and aforesaid annular wall. 50

2. A gas producer having in combination 55 a rotatable grate comprising a centrally located grate portion proper provided with openings adapted to admit the air or steam blast, an annular wall carrying said grate portion, an annular horizontal clinker platform around said wall and at a lower level than said grate portion, an outer shell or 60 wall and a refractory lining carried thereby and terminating above said clinker platform to thereby provide a clinker receptacle 65 thereon, said shell having an outlet from said receptacle, and a scraper at said outlet and extending completely across said clinker chamber flush with said refractory lining and aforesaid annular wall, and adapted to 70 remove ashes from said clinker platform and from said annular wall.

3. A gas producer having in combination 75 a rotatable grate comprising a centrally located grate portion proper provided with 80 openings adapted to admit the air or steam blast, an annular wall carrying said grate portion, an annular horizontal clinker platform around said wall and at a lower level than said grate portion, an outer shell or 85 wall and a refractory lining carried thereby and terminating above said clinker platform to thereby provide a clinker receptacle thereon, said shell having an outlet from said receptacle, a guideway attached to 90 said shell at said outlet and a removable scraper comprising a plate adapted to enter said guideway and be supported therein and extending across said clinker receptacle to fit against aforesaid rotary annular wall. 90

In testimony whereof, I the said PHILIP VON ZEIPEL have hereunto set my hand.

PHILIP VON ZEIPEL.
